WELL PUMP

Wilbur J. Crites, Bartlesville, Okla., assignor to
Phillips Petroleum Company, a corporation of
Delaware

Application May 12, 1941, Serial No. 393,105

4 Claims. (Cl. 163—244)

This invention relates to deep well pumps, more particularly it relates to oil well pumps employing air or gas pressure to lift oil from the well.

An object of this invention is to improve pumps of the general type disclosed in the U. S. Patent No. 2,202,970, granted to Steele, June 4, 1940, and other similar devices using a sliding or sleeve valve.

A further object of the invention is to provide a control valve for such structure of the poppet type operated by a cam.

Another object of this invention resides in its simplicity of design, small number of working parts, and economics of operation obtained through use of a control valve of the type disclosed which gives a rapid opening and closing of the gas inlet passages and eliminates the slippage occurring where there is a gradual opening and closing as in a valve of the sleeve type.

Still other objects and advantages of this invention will be apparent to those skilled in the art from the following detailed description, in conjunction with the accompanying drawing forming a part of this specification and in which:

Figure 1 is an elevation view of the pump structure positioned in a well bore and showing the well casing, tubing strings, and surface equipment;

Figure 2 is a vertical sectional view of the pump showing the control valve closed preventing gas under pressure from entering the fluid chamber;

Figure 3 is a transverse sectional view through the pump taken on the line 3—3 of Figure 2;

Figure 4 is a similar view taken on the line 4—4 of Figure 2; and

Figure 5 is a similar view taken on the line 5—5 of Figure 2.

In general the device forming the subject matter of the instant application comprises pumping apparatus which may be located at the bottom of a well, having a valve controlled by rotation of a tubing string from the surface which admits high pressure air or gas at the proper intervals to a fluid accumulation chamber and thereby lifting the fluid to the surface.

Referring now more particularly to the drawing, the numeral 10 generally designates the well bore in which fluid from the formation collects. A well casing 12 is shown in which there is an outer tubing string 13 and an inner tubing string 18 suspended in the customary and usual manner from the well head. Perforated bull plug 11 is attached to the lower end of outer tubing

string 13 and forms a space 16 within the tubing and below the pump for the accumulation of well fluid. As shown in Figure 1, the well head also comprises a drive head 14 adapted to rotate the inner tubing string, with a high pressure gas inlet 16, and a fluid outlet 18.

Threaded to the exterior on the lower end of inner tubing string 18 is a coupling or valve body adapter 21 in which is threaded the valve body 25. This valve body has a bore 26 extending through it from the upper to the lower face. Within the valve body is a second bore 28 having its lower portion of reduced diameter to form an annular shoulder 30 and its upper portion threaded to receive a valve guide and cap 29.

Positioned within bore 28 and guided by cap 29 is valve 22 of the poppet type having a coiled spring 23 on the upper part of the valve stem which normally holds the head 40 seated on the annular shoulder 30. The lower part of this valve stem extends through the lower part of bore 28 leaving the annular space 41 open for the passage of gas as hereinafter described.

A horizontal passage 42 through the side of valve body 25 places the exterior thereof, space 29, in communication with bore 28. Threaded into the exterior of this passage is a restricted orifice plug 24.

The lower end of valve body 25 terminates in the bearing surface 43. Ball bearings may be used at this point if preferred although applicant prefers a bronzed sliding surface. Contacting this surface is the upper end of the lower valve body adapter 32. A retaining flange 21 secured within a recessed portion of this adapter and fastened by flange screws 33 to the lower end of valve body 25, has a bore 44 and a smaller bore 45 extending through it, through which the lower end of valve 22 extends.

Attached to the lower end of this adapter 32 is a cam body 48 having a central bore 46 extending through it and a cam 28 positioned on its upper end. See Figures 2 and 3. Screwed into the lower end of bore 46 is a standing valve 14 with a ball 15 as customarily used in pump equipment for oil wells. A packer 17, threaded to the exterior of the cam body, closes the annular space 29 between the outer and inner tubing strings 13 and 18, and supports the cam body 48 and the valve body adapter 32 in position.

It will be seen from this construction that the valve body 25 attached to the inner tubing string 18 is free to rotate and the cam body 48 is held firmly in place by packer 17 with a bearing surface 43 being provided.

In operation, the inner tubing 36 is rotated by means of the drive head 34 at the well head. High pressure gas is admitted through gas inlet 38 at the surface and passes down through the annular space 29 between the inner and outer tubing strings. Packer 17 closes this space at the bottom, the gas is thus forced through the orifice 24 in valve body 28 through passage 42 and into bore 38, helping spring 23 hold valve head 40 seated on shoulder 39.

This pump to obtain its maximum efficiency must be placed deep enough in the well so that fluid from the formation will fill space 31 between casing 12 and tubing string 13, and space 18, unseating ball 15 and flow up through standing valve 14, bore 19, bore 44, and into bore 28, or even part way up into space 31 in the inner tubing string 36.

Then upon rotation of tubing string 36, valve body 28 will be rotated, valve 22 will engage with cam 26 and be raised against the pressure of spring 23 and the gas in bore 38. Gas will flow from this bore through the annular space 41 and up through bore 28 forcing the well fluid up through space 31 to the surface. When gas is admitted from bore 38 the pressure on the well fluid will close ball 15 in standing valve 14 and the producing formation will be protected from the high pressure gas and the fluid trapped above ball 15 will be forced from the pump passages, through the inner tubing string to the surface and out of the discharge pipe 35.

While applicant has described a specific embodiment, it is to be understood that the form of this invention, herewith shown and described, is a preferred example only and that various modifications may be made therein without materially departing from the spirit of this invention as defined by the appended claims.

For example, applicant for the sake of brevity has omitted a description and drawing of his invention using only a single rotatable tubing string 36, eliminating the outer string of tubing 13, and with packer 17 attached to the inner wall of the well casing 12 instead as shown. It is believed that such a change would be obvious to those skilled in the art and is inherent in applicant's invention.

Having thus described my invention, I claim:

1. In deep well lifting apparatus having rotatable inner tubing disposed within outer tubing and forming an annular space therewith, a source of high pressure gas communicating with the annular space, surface means for rotating the inner tubing, and a pumping mechanism having a fluid accumulation chamber communicating with the inner tubing, a passage in the pumping mechanism establishing communication between the annular space and the fluid accumulation chamber, said passage alternately opening and closing to admit gas at regular intervals into the fluid accumulation chamber, the improvement in the pumping mechanism comprising a valve body connected to the inner tubing and rotatable therewith, a gas inlet passage in the valve body, a valve within the valve body for opening and closing the gas inlet passage, a fluid passage extending through the valve body, a cam body associated with the valve body, a cam on the cam body cooperating with the valve to actuate the valve at regular intervals, a check valve controlled passage in the cam body, and means for preventing rotation of the cam body with respect to the valve body.

2. In deep well lifting apparatus having rotatable inner tubing disposed within outer tubing and forming an annular space therewith, a source of high pressure gas communicating with the annular space, surface means for rotating the inner tubing, and a pumping mechanism having a fluid accumulation chamber communicating with the inner tubing, a passage in the pumping mechanism establishing communication between the annular space and the fluid accumulation chamber, said passage alternately opening and closing to admit gas at regular intervals into the fluid accumulation chamber, the improvement in the pumping mechanism comprising a valve body attached to the inner tubing and having a fluid passage therein communicating with the inner tubing string and a gas inlet passage communicating with said fluid passage, a valve within the valve body for controlling the flow of gas through the gas inlet passage, cam means adapted to actuate the valve at regular intervals, a check valve controlled fluid passage in the cam means communicating with the fluid passage in the valve body, and a packer for closing the annular space between the inner and outer tubings and for preventing rotation of the cam body with respect to the valve body.

3. In deep well lifting apparatus having rotatable inner tubing disposed within outer tubing and forming an annular space therewith, a source of high pressure gas communicating with the annular space, surface means for rotating the inner tubing, and a pumping mechanism having a fluid accumulation chamber communicating with the inner tubing, a passage in the pumping mechanism establishing communication between the annular space and the fluid accumulation chamber, said passage alternately opening and closing to admit gas at regular intervals into the fluid accumulation chamber, the improvement in the pumping mechanism comprising a valve body having a valve therein connected to the inner tubing to control flow through the passage, a cam secured to the outer tubing, said valve rotating with respect to the cam upon rotation of the inner tubing and said cam on seating said valve at regular intervals to open the passage in the valve body.

4. In deep well lifting apparatus having inner tubing disposed within outer tubing and forming an annular space therewith, a source of high pressure gas communicating with the annular space, surface means for rotating the inner tubing, and a pumping mechanism having a fluid accumulation chamber communicating with the inner tubing, a passage in the pumping mechanism establishing communication between the annular space and the fluid accumulation chamber, said passage alternately opening and closing to admit gas at regular intervals into the fluid accumulation chamber, the improvement in the pumping mechanism comprising a cam body secured to the outer tubing, a valve body secured to the end of the inner tubing and rotatable therewith engaging the top of the cam body, a fluid passage in the valve body, a valve in the valve body coacting with the cam body for opening and closing the passage in the valve body at regular intervals.

WILBUR J. CRITES.
